(57) CLAIM

The ornamental design for a firearm hanger, as shown and described.

DESCRIPTION

FIG. 1 is a perspective view of the firearm hanger showing our new design;

FIG. 2 is a front view thereof;

FIG. 3 is a top view thereof;

FIG. 4 is a right side view thereof;

FIG. 5 is a left side view thereof;

FIG. 6 is a rear view thereof;

FIG. 7 is a bottom view thereof; and,

FIG. 8 is a perspective view thereof.

The broken lines shown in the drawings illustrate portions of the firearm hanger that form no part of the claimed design. The broken lines in FIG. 8, showing the firearm hanger in use, illustrate environment and forms no part of the claim.
